UNITED STATES PATENT OFFICE.

DAVID H. HARNLY, OF CHICAGO, ILLINOIS.

AWNNG-GUIDE.

1,357,048.

Specification of Letters Patent.

Patented Oct. 26, 1920.

Application filed October 28, 1918. Serial No. 259,926.

To all whom it may concern:

Be it known that I, DAVID H. HARNLY, a citizen of the United States, and a resident of the city of Chicago, in the county 5 of Cook and State of Illinois, have invented certain new and useful Improvements in Awning-Guides; and I do hereby declare that the following is a full, clear, and exact description of the same, reference being had to the accompanying drawings, and to the numerals of reference marked thereon, which form a part of this specification.

In the construction of awnings wherein 15 an extending bracket is secured to the lower margin of the awning fabric and has the ends thereof engaged slidably with stationary guide members, it has been found that as the awning fabric is pulled down, the 20 extending bracket, upon striking a stop, frequently falls inwardly toward the window instead of outwardly as desired. Considerable trouble is therefore often experienced in releasing the extending bracket to 25 make the same fall outwardly to extend the lower portion of the awning fabric.

This invention relates to an improved form of a guide for the extending bracket of an awning, said guide being formed and 30 mounted to prevent the inward throw of the extending bracket when the awning fabric is lowered.

It is an object of this invention to construct an awning wherein the fabric extending bracket always falls outwardly to extend the fabric when the guide ends of said bracket strike the guide stops.

Another object of the invention is the construction of an awning having guide 40 members for the extension bracket which serve to prevent said bracket from falling inwardly past dead center when the awning fabric is pulled down.

It is a further object of this invention 45 to provide guides for the extension bracket of an awning, said guides consisting of a plurality of standard parts adapted to be readily assembled to fit any size window.

It is furthermore an object of this invention 50 to provide awning extension bracket guides adapted to be mounted upon the outer surfaces of the vertical side members of a window frame to prevent the extension bracket when lowered from falling inwardly toward the window instead of out-

wardly an object of the invention to construct awning guides wherein standard supports are provided for receiving guide channels of any desired length.

60

It is an important object of this invention to construct an awning having guides to insure proper operation of the awning fabric extension bracket.

65

Other and further important objects of the invention will be apparent from the disclosures in the drawings and specification.

The invention (in a preferred form) is illustrated in the drawings, and hereinafter more fully described.

70

On the drawings:

Figure 1 is a front or outer view of a window equipped with an awning having guides embracing the principles of this invention.

75

Fig. 2 is an enlarged detail section taken on line 2—2 of Fig. 1.

Fig. 3 is an enlarged detail view illustrating a locking means for the detachable cross rod at the middle of the window 80 frame.

Fig. 4 is an enlarged front detail view of a pivoted gravity lock for the extension bracket of the awning.

Fig. 5 is an enlarged fragmentary detail 85 front view of one of the extension bracket guides.

Fig. 6 is an enlarged fragmentary detail section taken on line 6—6 of Fig. 2.

Fig. 7 is an enlarged detail section taken 90 on line 7—7 of Fig. 5, showing one arm of the extension bracket in elevation and seated in horizontal extended position.

Fig. 8 is a fragmentary detail section taken on line 8—8 of Fig. 7, with the extension bracket omitted.

Fig. 9 is a fragmentary detail section taken on line 9—9 of Fig. 7.

Fig. 10 is an enlarged fragmentary detail section taken on line 10—10 of Fig. 5.

100

Fig. 11 is a detail sectional view taken on line 11—11 of Fig. 10.

As shown on the drawings:

The reference numeral 1, indicates the wall of a building, and secured in a window aperture of said wall is a sash frame comprising a sill or lower member 2, a top member 3, and side members or stiles 4 and 5. Slidably mounted in the window frame are upper and lower window sashes 6 and 7, respectively. Mounted at the upper end 110 of the window frame on each side thereof

105

110

are roller brackets 8, suitably apertured or slotted to detachably receive the trunnions 9, of an awning roller 10. The upper edge of an awning fabric 11, is attached to the 5 roller to permit winding of said fabric thereon. One end of a pull or actuating cord 12, is attached to the awning roller, and is adapted to be rolled around said roller with the awning fabric. The pull cord 12, 10 extends downwardly and extends through a cleat pulley 13, which is securely mounted in position centrally upon the window frame sill member 2.

An angle bracket plate 14, is mounted 15 about midway between the upper and lower ends of the window frame stile 4. Said bracket plate is provided with an aperture to pivotally receive engaged therethrough a hook member 15, which is secured to one 20 end of a brace or cross rod 16. The other end of the cross rod 16, is bent over at an angle. A notched bracket plate 17, is rigidly secured to the frame stile 5, opposite from the bracket plate 14, and is adapted 25 to removably receive the free end of said cross rod 16, seated in the notch thereof. A pivotally mounted gravity acting retaining pawl 18, is mounted on said bracket plate 17, acting normally to lock the free 30 end of said cross rod 16, therein, and further acting to wedge said rod more tightly in the notched bracket plate 17, if there is a tendency for the rod to be swung up without first releasing the pawl. When swung upwardly the pawl 18, permits retraction of 35 the end of said cross rod, from the notched plate, so that said rod may swing downwardly alongside of the window frame into a position out of use, for instance, during 40 the cleaning of the window glass. If preferred, the awning may be used without the cross rod to permit the awning fabric to fall or be extended outwardly from the top, instead of holding the upper portion of 45 the fabric disposed in the plane of the window, as is the case when the cross rod is in horizontal position.

Connected to the lower hemmed margin of the awning fabric, is a U-shaped extending bar or bracket 19, having secured upon the ends of the arms thereof end caps 20, each of which has integrally formed to one side of the outer end thereof a longitudinally projecting outwardly directed angle arm 55 21, having integrally formed on the end thereof an enlarged gudgeon guide head 22.

To properly guide the extension bracket 19, in its downward and upward movements with the awning fabric 11, guide mechanisms 60 are provided on the front or outer surface of each of the window frame stiles 4 and 5, intermediate the ends thereof. The guide mechanisms are interchangeable, either one is right or left, and each 65 braces a plurality of standard parts adapt-

ed to be securely mounted in position to afford a proper guide length to fit substantially any size of window frame. Each guide mechanism comprises a unitary or one piece lower guide support or holder 70 consisting of an apertured mounting plate 23, having integrally formed at right angles to the upper edge thereof a shoulder or flange 24. Integrally formed at right angles to the shoulder 24, is an upwardly 75 projecting rectangular box or channel socket embracing a rear or back wall 25, side walls 26, and a front wall 27. The channel socket is open at the top. Stamped from the rear wall 25, of the socket is an 80 inwardly directed lock lug or tongue 28. The front wall 27, is provided with a longitudinal central slot 29. The lower margins of the side walls 26, are bent inwardly at right angles to afford lugs, flanges or 85 projections 30 and 31 projecting inwardly an amount equal to the width of the respective front wall portions to afford an opening in the bottom of the socket equal in width to the width of the slot 29. The lower 90 ends of the front wall portions are bent rearwardly at right angles below the flanges 30 and 31, to form brace members 32 and 33, respectively. It will thus be seen that the slot 29, is continued back to the rear 95 wall of the socket, and that the flanges 30 and 31, afford suitable stops which are braced by the brace members 32 and 33. The lower guide holders are secured to the lower portions of the front surfaces 100 of the window frame stiles 4 and 5, by means of screws 34, which engage through the apertures in the holder mounting plates 23.

Projecting into the open top of each guide 105 holder and seated or resting on the lock lug 28, is the lower end of a rectangular cross sectioned channel guide tube 35, the front wall of which is provided with a longitudinal guide slot 36, disposed to register with the 110 holder slot 29, as clearly shown in Fig. 5.

In mounting the guide mechanisms the gudgeon heads 22, of the extension bracket 19, are inserted through the open upper ends of the guide tubes 35, with the angle arms 115 21, engaged in the guide slots 36. Top or upper guide holders are next engaged over the upper ends of the guide tubes, and are secured to the front or outer surfaces of the 120 respective window frame stiles 4 and 5, by means of screws 37. Each upper guide holder is of unitary construction and comprises an apertured mounting plate 38, having integrally formed at right angles to the lower edge thereof a flange or shoulder 39. Formed integrally at right angles to the shoulder 39, is a downwardly projecting rectangular box or channel socket embracing a rear or back wall 40, side walls 41, and a front wall 42. The channel socket is open 130

at both ends. The upper margins of the side walls 40, are bent inwardly over the upper ends of the side walls of the respective guide tube 35, to form retaining lugs or 5 projections 43, to prevent removal of the guide tube and to hold the same rigidly in position. The front wall 42, is provided with a longitudinal slot 44, which registers with the guide slot 36, of the guide tube 10 above which the holder is mounted.

As shown in Figs. 1 and 4, a weighted or gravity acting lock 45, is pivotally mounted upon an outwardly projecting bracket, the inner end of which is secured on the lower 15 portion of the window frame stile 5, to normally position the locking hook 46, of the lock 45, in front of the lower portion of the guide slot 29. Integrally formed on the lock 45, below the hook 46, is a release arm 20 or tongue 47.

The operation is as follows:

The roller 10, on which the awning fabric 11, is attached, is first mounted in position by engaging the roller trunnions 9, in the 25 roller brackets 8. When the fabric is rolled up on the roller, the extension bracket 19, hangs downwardly from the lower margin of the fabric as shown in Fig. 2. The lower interchangeable guide tube holders 23-33, 30 are next secured upon the lower portions of the front or outer surfaces of the respective window frame stiles 4 and 5, by means of the screws 34. The gudgeon heads 22, of the extension bracket 19, are then engaged 35 through the open upper ends of the channel guides or tubes 35, with the angle arms 21, slidably engaged in the guide slots 36, and projecting outwardly therethrough. The lower ends of the guide tubes 35, are then 40 projected into the open upper ends of the lower holders and rest or seat upon the lock lugs 28, as clearly shown in Figs. 7 and 8, in which position the guide slots 36, register with the holder guide slots 29. The upper 45 guide tube holders 38-43, are now engaged over the upper ends of the guide tubes 35, with the retaining lugs 43, seated upon the upper edges of the side walls of the guide tubes, in which position the upper holders 50 are rigidly secured by means of screws 37, to the front of the window frame stiles 4 and 5, to rigidly hold the guide tubes in vertical position in front of the window frame, and behind the arms of the extension 55 bracket 19, as shown in Fig. 2. The guide tubes 35, may be cut to fit any size window and may be engaged in the sockets of the standard upper and lower guide holders as described.

60 As shown in Fig. 4, the gravity lock 45, is pivotally mounted in front of the lower guide holder on the window frame stile 5. The cross brace rod 16, at the middle of the window frame has the free end thereof engaged in the notched bracket plate 17, and is

removably locked in position by the gravity acting retaining pawl 18, which serves to wedge said rod more tightly in the notched plate, if there is any tendency for the rod to swing upwardly. The rod 16, is disposed in 70 front or to the outside of the guide tubes and serves when in horizontal position to confine the upper portion of the awning fabric in the plane of the window frame. The rod 16, may be readily swung into position out of use by merely moving the gravity pawl 18, upwardly, and withdrawing the rod to permit the same to swing downwardly alongside of the window frame. 75

The upper end of the pull cord 12, is attached to the roller 10, and is adapted to roll around the roller with the awning fabric. With the awning parts assembled as shown in Fig. 1, to lower the awning the cord 12, is pulled through the cleat pulley 13, thus 80

rotating the curtain or shade roller 10, against the stress of its internal spring. With the downward movement of the shade, the extension bracket 19, is adapted to slide 85 downwardly by gravity in the guide slots 90 36, until the gudgeon heads 22, pass downwardly in front of the lock lugs 28, and strike against the stops 30-31, in the bottom of the lower guide holder sockets. Due to the novel arrangement of the guide mechanisms on the front surfaces of the window frame stiles 4 and 5, the arms of the extension bracket 19, are always disposed in front 95 of said guide mechanisms during the upward and downward movement of the awning, and consequently said guide mechanisms serve to prevent the extension bracket from falling inwardly past dead center toward the window when the gudgeon heads 100 22, strike the stops 30-31. Upon striking the stops 30-31, the extension bracket 19, therefore always swings or falls outwardly into a position slightly below horizontal thereby striking the gravity lock 45, which 105 swings to permit one arm of said extension bracket to pass below the lock hook 46. The lower weighted end of the gravity lock 45, serves to swing the upper end thereof back into normal position to permit one arm of the extension bracket 19, to lockingly engage 110 115 beneath the locking hook 46, of said gravity lock as shown in Fig. 4. The extension bracket is thus held extended in substantially a horizontal position against the action of the roller spring, to hold the lower portion of the awning fabric 11, below the rod 16, extended outwardly from the plane of the window frame. To release the awning a short pull is exerted on the cord 12, whereby the arm of the extension bracket 120 125 19, engaged below the hook 46, strikes against the lock arm 47, causing the lock 45, to swing on its pivot to release the extension bracket, whereby the action of the roller spring acts to automatically roll the 130

awning fabric upon the roller drawing the extension bracket 19, upwardly therewith in front of the guide mechanisms.

One of the important features of the invention is the arrangement and the mounting of the interchangeable guide mechanisms on the front surfaces of the window frame stiles in position to always insure an outward swinging movement of the extension bracket 19, when the gudgeon heads 22, thereof strike against the stops 30-31. It will therefore be noted that the upper holders of said guide mechanisms serve as stops to hold the extension bracket from falling inwardly toward the window beyond dead center to prevent proper operation of the awning.

The upper guide holders and the guide tubes are open at the top to permit the gudgeon heads 22, of the extension bracket 19 to be inserted in position after the upper guide holders are mounted on the window frame. The extension may also be removed from engagement with the guide mechanisms when desired without removing any of the mounting screws of the guide tube holders.

I am aware that many changes may be made, and numerous details of construction may be varied through a wide range without departing from the principles of this invention, and I therefore do not purpose limiting the patent granted otherwise than necessitated by the prior art.

35 I claim as my invention:

1. The combination with an awning and the extension bracket thereof, of slotted stationary guide means for said extension bracket acting as stops against the inward 40 swing of said extension bracket when the awning is operated.

2. The combination with an awning, of a mounting comprising longitudinally slotted guides secured on the front surfaces of an awning support, and an extension bracket attached to said awning and slidably engaged in said guides which guides also serve as stops to hold said bracket against falling inwardly toward the support when the awning is operated.

3. The combination with an awning adapted to be mounted on a building or structure, of an extension bracket attached to said awning, lower guide holders attached to said structure, guides seated therein, said bracket slidably engaged in said guides, and upper guide holders mounted on said structure to receive the upper ends of said guides to hold the same in position, said upper guide holders also serving as stops adapted to be contacted by said bracket to hold the same from swinging inwardly toward the structure thereby insuring proper operation of said bracket when the awning is lowered.

4. The combination with an awning 65 mounted in a window frame, of an extension bracket attached to said awning, and a guide mechanism for said bracket secured to the front surface of said window frame and embracing a slotted lower holder, a slotted 70 guide tube seated therein and having said bracket slidably engaged therewith, and a slotted upper holder engaging the upper end of said guide tube to hold the same in position and also serving as a stop for said 75 bracket to insure an outward throw thereof when the awning is lowered and the bracket strikes said lower holder.

5. The combination with an awning for mounting in a window frame or the like, of 80 an extension bracket forming a part thereof, and a guide mechanism for said bracket secured to the window frame and comprising a slotted lower holder, stops formed thereon, a lock lug formed in said lower holder, a 85 slotted channel guide engaged in said lower holder and resting on said lock lug, and an upper holder engaged on the upper end of said guide tube and secured to said frame to hold the guide tube in position, said upper 90 holder also acting as a stop for said bracket to insure an outward throw thereof when the awning is lowered and said bracket strikes against said lower holder stops whereby said bracket is swung outwardly 95 into substantially horizontal extended position and lockingly engaged below said lock lug.

6. The combination with an awning extension bracket, of a frame guide mechanism 100 therefor embracing a slotted lower holder, stops integral therewith, an integral lock lug formed in said lower holder, a slotted channel guide projecting into said lower holder and seated on said lock lug, an upper holder 105 engaged on the upper end of said channel guide and secured to said frame to hold said channel guide in position, and lugs integral with said upper holder to hold said channel guide against upward movement, said bracket being slidably engaged with said channel guide and adapted when lowered to strike said lower holder stops and swing outwardly to engage beneath said lock lug.

7. A guide mechanism for an awning extension bracket, said mechanism embracing a slotted lower holder, a slotted guide channel engaged and supported therein, and a slotted upper holder engaged on said guide channel to hold the same in position, said 110 slotted members being assembled with the slots therein registering with one another to form a continuous guide slot to permit sliding operation of the bracket therein.

8. The combination with an awning extension bracket, of a guide mechanism comprising a slotted lower holder, a slotted guide tube supported therein, and a slotted upper

holder engaged on the upper open end of said guide tube to hold the same in position, said upper holder being open at the top to removably receive the extension bracket to permit the same to slidably operate in the continuous guide slot formed by the registering slots of said holders and said guide tube.

In testimony whereof I have hereunto subscribed my name in the presence of two subscribing witnesses.

DAVID H. HARNLY.
